INVENTOR.

UNITED STATES PATENT OFFICE.

ALFRED H. GERLACH, OF CHICAGO, ILLINOIS, ASSIGNOR TO THE MEYERCORD COMPANY,
OF CHICAGO, ILLINOIS.

DESIGN FOR A PLATE OR SIMILAR ARTICLE.

50,886.

Specification for Design.

Patented June 5, 1917.

Application filed April 9, 1917. Serial No. 160,900. Term of patent 3½ years.

To all whom it may concern:

Be it known that I, ALFRED H. GERLACH, a citizen of the United States, residing at Chicago, in the county of Cook, State of Illinois, have invented a new, original, and ornamental Design for an Article of Manufacture, of which the following is a specification, reference being had to the accompanying drawing, forming a part thereof.

The figure is a plan view of a plate broken away in part, showing my new design.

I claim—

The ornamental design for an article of manufacture as shown.

A. H. GERLACH.

Witnesses:

JAMES W. BRADY,
C. WESTERLIND.
